COMBINATION HOE, CUTTER AND EDGER FOR GARDENING

Angelo De Feo, Jr., 664 Riverview Drive,
Totowa Borough, N.J. 07512

Filed Dec. 26, 1967, Ser. No. 9,909

Term of patent 14 years

Int. Cl. D8—01

U.S. Cl. D8—11

FIG. 1

FIG. 2

FIG. 1 is a side view of a combination hoe, cutter and edger for gardening showing the blade positioned for a hoe.

FIG. 2 is the top view showing the blade positioned for a hoe.

FIG. 3 is the front view showing the blade positioned for a hoe.

FIG. 4 is the front view showing the blade positioned for an edger.

FIG. 5 is the top view showing the blade positioned for a cutter.

The handle in the above views are foreshortened for the convenience of illustration.

I claim:

The ornamental design for a combination hoe, cutter and edger for gardening, as shown and described.
